UNITED STATES PATENT OFFICE.

PETER J. FONOS, OF NEW RICHMOND, WISCONSIN.

RAIL-JOINT.

1,210,785.

Specification of Letters Patent. Patented Jan. 2, 1917.

Application filed August 25, 1915. Serial No. 47,296.

To all whom it may concern:

Be it known that I, PETER J. FONOS, citizen of the United States, residing at New Richmond, in the county of St. Croix and State of Wisconsin, have invented certain new and useful Improvements in Rail-Joints, of which the following is a specification.

My invention relates to railway rail joints and more particularly to rail joints of the type including complementary interlocking rail terminals or ends.

An object of the invention is to generally improve railway rail construction whereby the splice or joint may be made rigid and secure against both lateral and vertical strain.

A further object of the invention is to provide an improved and simplified retaining means for releasably locking the rail ends in engagement one with the other.

I still further contemplate an improved means whereby the retaining element may be fastened or secured.

The above and additional objects are accomplished by such means as are illustrated in their preferred embodiment in the accompanying drawings, described in the following specification and then more particularly pointed out in the claim which is appended hereto and forms a part of this application.

In describing my invention in detail reference will be had to the accompanying drawings wherein like characters denote like or corresponding parts throughout the several views, and in which:

Figure 1 is a top plan view of my improved rail joint, the complementary or interlocking rail terminals having been separated, and the retaining element and locking means removed; Fig. 2 is an end view of one of the meeting rails, the retaining element and lock means being shown in section; and Fig. 3 is a side elevation, the parts constituting the rail joint being shown in assembled relation.

Referring now to the drawings by numerals, 1—1 designates the respective interlocking railway rails, 2 as an entirety the retaining element and 3 as an entirety the fastening means whereby the retaining element is held in place.

The base flange portion of each rail 1 is cut at an acute angle to the longitudinal axis of the rail or as indicated at 4, the

angular faces of the respective rails being adapted for abutting engagement in the assembled position of the rail-joint parts. The web and tread portion of each rail is likewise cut at an acute angle to the longitudinal axis of the rail, the angle however extending oppositely and transversely of the angle of the base flange, yet in such relation thereto as to cause the angular faces 5 to engage when the angular faces 4 shall have been engaged in the manner stated.

By the rail construction above noted it is evident that a portion of the web and tread of one of the rails 1 will overlap a portion of the base flange of the other of the said rails when the said rails shall have been forced into locking relation. It will be further observed that by the overlapping arrangement above noted both lateral and vertical displacement is prevented and the rail terminals are held in aligned relation so long as the abutting engagement is maintained. The engagement of the angular faces 4—4 and 5—5 will preclude lateral displacement of the rails 1 while the engagement between the overlapping portions of the respective rails will preclude vertical displacement.

Openings 6 are formed in the rails 1 adjacent the ends thereof, the openings of one rail being adapted for registration with the openings in the complementary rail to provide, when thus registered, continuous openings through which pins 7 are adapted to pass. The said pins 7 are made integral with a retaining plate 8 and with the said plate they constitute the retaining means 2. When the rail terminals are fastened in abutting relation, the said plate 8 is adapted for engagement with the web portion of the respective rails 1 to provide in effect a fish plate of an accepted or common design. Each retaining pin 7 is provided with a transverse opening 9 adjacent its free end. The purpose of the mentioned openings will be hereinafter described.

Coming now to a description of the means for locking the retaining element against displacement while in use, 3, as before stated, designates as an entirety the mentioned means. Said means in its preferred embodiment may be said to consist of a plate member 10 apertured as indicated at 11, each of the mentioned apertures being somewhat elongated as shown to advantage in Fig. 3.

Locking pins 12 are made integral with the mentioned plate 10 to extend longitudinally of the apertures 11, the said pins 12 in the assembled relation of the rail-joint parts, being adapted for fitting engagement with the openings 9 of the retaining pins 7 noted above. A head 13 is formed at one end of the plate 10 that the said plate may be moved longitudinally of the railway rails 1 in assembling and disassembling the rail-joint parts. Said plate 10, like the plate 8 forms in effect a fish plate of an accepted design.

In assembling the parts constituting my improved rail joint, the rails 1 are first placed in alined relation and moved into engaging proximity or until the angular faces 4-4 and 5-5 abut. Movement of the rails 1 in the manner stated will cause the openings 6 within the respective rails to aline. The retaining element 2 is next brought into place, the retaining pins 7 fitting the openings 6 and the plate 10 abutting the interlocking rails. The said element 2 will preclude longitudinal movement or separation of the rails. The parts having been thus assembled it is but necessary that the locking means 3 be placed properly with respect to the retaining pins 7 in order that the rails 1 may be effectually joined. In arranging the plate 10 properly against the rails 1, said plate is so positioned relatively to the retaining pins 7 as to fit the said pins 7 in the apertures 11. When thus positioned, the plate 10 is moved longitudinally of the rails until the locking pins 12 shall have passed through the openings 9 in which event the rails are properly and effectually joined.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claim.

Having thus fully described my invention, what I claim as new and desire to secure by Letters Patent, is:—

In a rail joint, rails having their meeting base flanges cut at an acute angle to the longitudinal axis of the rail, and their tread and web portion cut at a corresponding angle in an opposite direction, to dispose the rail terminals in overlapping relation, transverse registerable openings provided in the overlapping portions, bolts adapted to enter said openings, to retain the rails against longitudinal displacement, a plate connecting said bolts, openings provided in the projecting ends of said bolts, a plate having elongated openings to receive the bolts and pins disposed in said openings for entering the openings in the bolts to retain the rail against lateral displacement.

In testimony whereof I affix my signature in presence of two witnesses.

PETER J. FCNOS.
